CLAIM

The ornamental design for a throwing toy, as shown and described.

DESCRIPTION

FIG. 1 is a top perspective view of a throwing toy, showing my new design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The broken lines shown in the drawings are for purpose of illustrating portions of the throwing toy and form no part of the claimed design.

The broken lines immediately adjacent to the solid lines at the top opening of the article in FIGS. 1 to 6 define the bounds of the claimed design and form no part thereof.

1 Claim, 7 Drawing Sheets
